WEBBING CLIP

Louis Fischer, Elmhurst, and Anton Schlussel, Bronx, N. Y.; said Fischer assignor to said Schlussel

Application February 1, 1956, Serial No. 562,780

4 Claims. (Cl. 24—84)

This invention relates to clips for securing webbing, and particularly to a clip for fastening the ends of strips of webbing to tubes in making backs or seats for tubular aluminum furniture. The present invention is an improvement over the disclosure in our co-pending patent application, S. N. 504,659, filed April 28, 1955, now abandoned.

It has heretofore been known in the art to use clips of V-shape cross section squeezed on the end of webbing strips and having a hook for engagement in slots provided in the walls of aluminum tubes in making foldable lawn furniture. However, experience with such clips as are known in the prior art reveals drawbacks in that they do not properly grip certain kinds of webbing having strands of circular cross section.

Accordingly, it is an object of the present invention to provide a clip which overcomes the above drawbacks of prior art clips, but which can be as cheaply manufactured.

It is a further object of the invention to provide a clip which will be durable and which will not readily slip out of place when applied by means of an integral hook to a slot in a tubing frame.

It is a particularly important object of the present invention to provide a clip so constructed that it may be made from aluminum.

In attaining these objects we provide a metallic clip having a pair of angularly related integral flanges which can be bent toward each other to clip the end of a webbing strip therebetween. One of these flanges is provided with a plurality of elongated dimples or ridges which project toward respective perforations of corresponding shape in the other flange. The arrangement is such that the ridges register with the perforations when the flanges are squeezed together so as to bulbously distort the web material along elongated lines and into respective perforations. This permanently locks the web to the clip regardless of the material of the web. We have found after exhaustive testing with particularly heavy stresses over a period of time that the use of elongated ridges rather than round dimples as shown in our previously filed application is a distinct improvement. At a matter of fact, a surprising result was revealed in the course of experiments and testing in the sense that clips following the teachings of the present disclosure may be made from aluminum and yet will hold with safety. Prior to this discovery all such clips were necessarily made from steel which is heavier and stronger than aluminum and which material was quite suitable with the structure shown in our prior application. However, there are distinct advantages in using aluminum rather than steel. Firstly, there is no electrolytic action set up when aluminum clips are placed contiguous with aluminum tubing in the making of tubular furniture. Steel clips have an electrolytic action which causes corrosion unless such clips are well plated.

2

Secondly, aluminum is easier to work, thereby effecting a saving in die cost.

Thirdly, aluminum is lighter, thereby effecting a saving in handling and shipping costs.

5 A detailed description of our invention will now be given in conjunction with the appended drawing in which:

Fig. 1 is a perspective of the device prior to being applied to a webbing strip.

10 Fig. 2 is a section through 2—2 of Fig. 1.

Fig. 3 is a front elevation.

Fig. 4 is a perspective showing the clip as applied to a webbing strip and ready to be applied to a tubing frame.

15 Fig. 5 is a section through a piece of tubing showing the clip of Fig. 4, as it appears when applied to a tubing frame.

With reference to the drawing, our improved clip comprises an integral angle of aluminum having flanges

10 and 12 joined in a bend line 16. Flange 10 is provided with two elongated perforations 18 which extend for a substantial distance on each half of the length of the clip, such distance being made as long as practical, consistent with leaving a suitable width of web at 22 at each end of the flange 10 and web 24 intermediate the slots and extending to a central slot 26 from which has been struck a hook 28 to be subsequently described. In an actual commercial embodiment the length of the slots 18 is between three and four times the width of any web 22 or 24. The flange 12 has stamped therefrom a pair of ridges or elongated dimples 30 so aligned

20 with respect to perforations 18 that when the clip is applied to a webbing strap 34 as shown in Figs. 4 and 5 the ridges 30 protrude into the slots 18 and securely lock elongated areas of the webbing strap therein. The 25 ridges as clearly disclosed on the drawing are generally rigid, bulbous formations having linear crests and are substantially incompressible in application to a strap and as clinched thereon.

30 We believe that an important aspect of our construction which gives us the surprising locking results obtained resides in the use of closed slots such as 18, the rounded closure edges 36 being clearly evident on Fig. 3. Apparently the effect of the closed slot is to grip and deform the webbing longitudinally of the clip while 35 stretching the webbing latitudinally, that is, along the long edge of the ridge. This produces a peculiarly effective type of grip in that even under stress far in excess of that normally encountered in use, the flanges 10 and 12 would not be spread apart so as to release the web. It is further our theory that the fibers of the web are compressed against the edges of the slot and provide a locking effect by compression and indentation of the fibers contiguous with the slot edges.

40 The effect of the above construction as described is 45 considerably superior to other arrangements which have been tried and marketed and although no microscopic examination has been made of the exact effect on the webbing strap produced by our novel coaction of elongated ridges and slots, rigid tests under working conditions leave no room for doubt as to the peculiarly increased holding power of the arrangement. As stated hereinabove, a very important advantage is obtained in that we are enabled to manufacture clips of aluminum rather than the relatively heavy and expensive cadmium-plated steel, which we previously used.

50 Attention is invited to Fig. 4 showing the clip as applied to a webbing strap 34 prior to application of the clip to an aluminum tube. In Fig. 5 the clip is shown as applied to an aluminum tube by means of the hook 28. 55 As set forth in our previous application, the hook 28 is fashioned with a rib 38 for reinforcement purposes and as stated in the previous application, the rib was intended

to prevent straightening out of the hook under load in the event the clip was made of aluminum. We now find, in view of the present novel structure for the web, that the mode of constructing the hook with a reinforcing rib 38 is of considerable importance, for obviously if the hook had any tendency to straighten out the purpose of the hook would be defeated. While there is a distinct possibility that certain types of hard and expensive aluminum could be utilized for our clip wherein the hook would not straighten out even though not provided with a rib, it should be apparent that the provision of the rib enables us to use softer and cheaper aluminum, thereby effecting a saving in material as well as in machining operations. Accordingly, we regard the novel structure of the hook as being a highly desirable feature to be used in conjunction with the presently disclosed web gripping elements.

Further, as disclosed in our prior application, a dimple 40 is disposed at the end of the hook to serve as a lock to prevent the hook from sliding out of the tubing slot 44.

In conclusion, we are aware that various modifications may be made without departing from the spirit of our invention and accordingly we do not seek to be limited to the precise illustration herein given except as set forth in the appended claims.

We claim:

1. A clip for securing webbing comprising a pair of angularly related flanges joined at a bend line and bendable at that line to permanently and non-detachably engage webbing placed between said flanges, one of said flanges being provided with a pair of elongated slots, the other of said flanges being provided with a pair of ridges stamped therefrom and co-acting with respective slots to define elongated clinching areas for permanently and deformingly clinching elongated areas of said webbing therein, said clip being provided with a hook for insertion in a slit through the side of a tube, said hook being struck from the material of one of said flanges,

15

20

25

30

35

said ridges being bulbous and having closed sides and being substantially non-compressible and having elongate linear crests, said hook being disposed intermediate the elongated clinching areas, the direction of elongation of the slots and ridges being substantially parallel to the bend line.

2. A clip as set forth in claim 1, the material thereof being sheet aluminum.

3. A clip as set forth in claim 1, said slots and ridges having symmetrically registerable, circular ends.

4. A clip as set forth in claim 3, the material of said clip being sheet aluminum.
